KNIFE

Alfred Storfer, Brooklyn, N. Y.

Application March 16, 1936, Serial No. 69,042

1 Claim. (Cl. 30—9)

This invention relates to improvements in knives and has for its main object to provide a knife for cutting furs, skins or the like, whose construction will be simple and of relatively small cost, and wherein just a section of a safety razor blade of the usual Gillette type can be utilized as a cutting edge.

Another object is to so construct the holder as to permit the mounting and replacement of the blade easily and quickly and which will effectively hold the blade in operative position against wobbling.

The hitherto known fur knives require use of specially shaped razor blades and their construction is unsatisfactory in that they are comparatively costly and that the blades cannot be firmly locked in position.

With these and other objects in view, my invention consists in the novel construction combination and arrangement of parts as will be hereinafter more fully described and defined in the appended claim.

In the accompanying drawing which constitutes part of this specification and in which similar reference characters denote corresponding parts:

Fig. 1 is a side elevation of my improved knife showing the blade locked in the holder.

Fig. 2 is a similar view showing the blade unlocked in the holder, and

Fig. 3 is section on line 3—3 of Fig. 1.

As cutting edge for my knife I utilize a half section of a razor blade R of the Gillette or similar type, formed by splitting the latter diametrically. I found that such half razor blade can be conveniently mounted and locked in operative position in a holder which constitutes my invention.

The holder comprises a flat mounting member or plate 10 of sheet metal of which the front or head portion 11 is tapered and formed with a cut out portion 11c and the rear portion 12 serves as a handle or grip.

The inclined front edge 11a of the head portion is longitudinally bent upon itself to form a bead or flange 11b which extends from the bottom edge to a point short of the peak or top end of the incline 11a. This bead is bent in such a manner as to form between itself and the inner face of the plate a laterally flaring or wedge shaped groove 11f (Fig. 3) which at the juncture of said bead and body portion of the plate is but slightly wider than the thickness of said razor blade R.

At a point spaced from the said bead the head portion 11 of said plate 10 is formed, by punch-

ing or otherwise, with a short stud or projection 11e to engage the usual hole R' of said razor blade whereby the latter can be centered on the plate so that its biased edge will extend through the groove 11f parallel to the front biased edge 11a of the head portion 11, while its cutting edge R² will project beyond the lower edge of the cut away portion 11c and its rear edge be in alinement with the shoulder 11d formed at the rear end of the cut away portion 11c.

At a suitable point, as at 13a, there is pivotally secured to said mounting plate 10 a flat locking member 13 of resilient sheet metal, whose front or head portion 13b is also tapered, the inclined edge 13c thereof conforming with the edge 11a of the plate 10 and whose rear end 13d serves as a handle. This inclined edge 13c is adapted when the locking member is turned on its pivot 13a in clockwise direction (Fig. 2) to enter the groove 11f and on exertion of sufficient pressure to wedge the razor blade R between itself and the plate 10 so as to firmly lock said blade in operative position.

In order to prevent said locking plate 13 from accidentally leaving the groove 11f, the stud 11e may be made a little higher than the thickness of the razor blade and the head portion of said locking member 13 may be provided on its inner face with a circular depression 13e to snap over and engage the stud 11e when the biased edge 13c of said member on passing into the groove 11f is substantially parallel with the edge 11a of plate 10.

The handle or rear portion 13d of said locking member 13, for the purposes of economy in material, may be considerably shorter than that of the base plate 10 and is so shaped that its lower edge 13g will be in alinement with or follow the contour of the lower edge 12a of the handle portion 12 of said mounting plate 10. Said handle 13d may be provided with a circular cut out 13f for the insertion of the finger tip whereby it may be conveniently turned into unlocking position.

The lower edge of the head portion 13b of said locking member 13 is also cut away as 13h to be in complete alinement with that of the mounting plate 10, so that after the blade has been wedged in operative position its cutting edge R² will be fully exposed.

From the foregoing it will be seen that a half section of a razor blade of the Gillette type can be conveniently utilized as cutting edge for my knife and that the same can easily and quickly be secured in my improved holder. It will also be

seen that by reason of the simplicity of construction its cost of production is reduced to a minimum.

Since various changes may be made in the construction of my device without departing from the principle of my invention, I do not wish to restrict myself to the details described and shown.

What I claim is:

In a knife for cutting fur or the like, the combination with a section of a razor blade of the Gillette type formed with a biased edge, of a holder for said blade section comprising a mounting plate whose front edge is biased to conform with a biased edge of the razor blade section

and is bent upon itself to form a wedge shaped groove adapted to engage said biased edge of said razor blade section, a centering stud on said mounting plate to pass through the hole of said razor blade section, a locking member pivoted to said mounting plate whose forward edge is adapted in locking position to engage said wedge shaped groove and produce a wedging effect on said blade section, thereby locking it in operative position and a depression on the inner face of said locking member to snap over said stud when it is in locking position. 5 10

ALFRED STORFER.
